US00D916779S

(12) **United States Design Patent** (10) Patent No.: **US D916,779 S**
 Zhu et al. (45) Date of Patent: ** *Apr. 20, 2021

(54) **DISPLAY SCREEN OR PORTION THEREOF WITH A GRAPHICAL USER INTERFACE**

(71) Applicant: **Beijing Kuaimaijidian Technology Co., Ltd.**, Beijing (CN)

(72) Inventors: **Jun Zhu**, Beijing (CN); **Ziyi Wu**, Beijing (CN); **Yanling Zhang**, Beijing (CN); **Siyan Zhou**, Beijing (CN); **Hui Sun**, Beijing (CN)

(73) Assignee: **Beijing Kuaimaijidian Technology Co., Ltd.**, Beijing (CN)

(*) Notice: This patent is subject to a terminal disclaimer.

(**) Term: **15 Years**

(21) Appl. No.: **29/667,564**

(22) Filed: **Oct. 23, 2018**

(30) **Foreign Application Priority Data**

(57) **CLAIM**

We claim the ornamental design for a display screen or portion thereof with a graphical user interface, as shown and described.

DESCRIPTION

The FIGURE is a front view of a display screen or portion thereof with a graphical user interface showing our new design.

The outermost broken line rectangle shows the display screen or portion thereof, and forms no part of the claimed design. All other broken lines show portions of the graphical user interface and form no part of the claimed design.

1 Claim, 1 Drawing Sheet
